CLAIM

The ornamental design for a housing for refrigerant recovery system, as shown.

DESCRIPTION

FIG. 1 is a perspective view of the design for a housing for refrigerant recovery system in accordance with a first preferred embodiment of the present invention;

FIG. 2 is a left elevational view of the housing for refrigerant recovery system of FIG. 1 (the right side being a mirror image of same);

FIG. 3 is a top elevational view of the housing for refrigerant recovery system of FIG. 1;

FIG. 4 is a bottom elevational view of the housing for refrigerant recovery system of FIG. 1;

FIG. 5 is a front elevational view of the housing for refrigerant recovery system of FIG. 1; and,

FIG. 6 is a back elevational view of the housing for refrigerant recovery system of FIG. 1.
